UNITED STATES PATENT OFFICE.

WILLIAM M. KARR, OF GOTHENBURG, NEBRASKA.

AUTOMATIC FOLDING DOOR.

Application filed August 28, 1924. Serial No. 734,785.

To all whom it may concern:

Be it known that I, WILLIAM M. KARR, a citizen of the United States, residing at Gothenburg, in the county of Dawson and 5 State of Nebraska, have invented certain new and useful Improvements in Automatic Folding Doors, of which the following is a specification.

This invention appertains to closures and 10 more particularly to doors for garages, the bodies of ice wagons and the like.

The primary object of the present invention is to provide a novel door or gate with an improved means for permitting the automatic opening of the door or gate upon 15 the release of a suitable catch or trip.

Another object of the invention is to provide a novel sectional folding door and novel means for automatically opening the 20 door one section at a time, the door being adapted to be folded upon itself during the opening movement thereof.

A further object of the invention is the 25 provision of novel means for holding the pivoted sections of the door in their folded position and novel means for holding the entire door in its opened position against accidental displacement.

A further object of the invention is to 30 provide releasable means for holding the sections of the door locked together in their collapsed position during the opening and closing movement of the door.

A further object of the invention is to 35 provide an improved door embodying a pair of pivotally connected sections, one of said sections being hingedly connected with one side of the door frame and novel means for engaging each door section for holding the 40 same against normal swinging movement, the outer door section being adapted to operate the holding means of the other door section to permit the swinging movement thereof when the first door section has been 45 released and opened to its full position.

A still further object of the invention is 50 to provide a novel closure of the above character which will be durable and efficient in use, one that will be simple and easy to manufacture and one which can be placed upon the market at a small cost.

With these and other objects in view, the invention consists in the novel construction,

arrangement and formation of parts, as will be hereinafter more specifically described, claimed, and illustrated in the accompanying drawings, in which drawings,

Figure 1 is a front elevation of the improved closure showing the same in its closed position and applied to a garage, 60

Figure 2 is a fragmentary side elevation of the garage showing the improved closure incorporated therewith,

Figure 3 is a fragmentary elevation looking from the opposite side of the garage 65 showing the improved closure incorporated therewith and illustrating the novel catch employed for holding the door in its closed position,

Figure 4 is a transverse section through 70 the garage taken on the line 4—4 of Figure 3 looking in the direction of the arrows and illustrating the inner face of the door, the door being in its closed position,

Figure 5 is a horizontal section through 75 the door and garage, showing the door in its closed position and illustrating the novel catch carried by the door sections for permitting the sections to be locked together during the opening and closing movement 80 of the door, the section being taken on the line 5—5 of Figure 4 looking in the direction of the arrows,

Figure 6 is a front elevation of the garage showing the door or closure in its fully 85 opened position,

Figure 7 is a horizontal section taken on the line 7—7 of Figure 6 showing the door in its fully opened position and illustrating the catch for holding the door open, 90

Figure 8 is a horizontal section through the door taken on the line 8—8 of Figure 6 looking in the direction of the arrows showing the door in its fully opened position and illustrating the novel releasable catch 95 for holding the door sections locked together,

Figure 9 is a vertical section through the door showing the door in its fully opened position and taken on the line 9—9 of Figure 7 looking in the direction of the arrows 100 and illustrating the means for holding the door in its opened position and the means for holding the sections of the door locked together,

Figure 10 is a detail vertical section taken 105

on the line 10—10 of Figure 1 illustrating the novel means utilized for holding the innermost section of the door in its closed position until the outer section of the door 5 has been swung to its opened position,

Figure 11 is a detail section taken on the line 11—11 of Figure 6 showing the catch utilized for holding the innermost door section in its closed position and the releasable 10 means carried by the outer section of the door for operating the catch.

Referring to the drawings in detail, wherein similar reference characters designate corresponding parts throughout the several 15 views the letter A generally indicates the improved closure and B a garage with which the same is associated.

It is to be understood that the closure A can be incorporated with any desired receptacle, vehicle body or the like, and the 20 same has been shown incorporated with a garage B in the drawing simply to illustrate the use and operation thereof.

The garage B can be of any desired construction and as shown includes the side walls 15 and 16 and the front wall 17 which is provided with an enlarged door opening 18 which can be surrounded by any preferred type of door frame.

30 The door A comprises a pair of companion sections 19 and 20 which are adapted to fold one upon the other during the opening and closing movement of the door. These sections 19 and 20 are hingedly connected together at their meeting edges by strap hinges 21 which consist of leaves 22 and 23 which extend the full width of the door sections 19 and 20. The inner ends of the leaves 22 and 23 are provided with aligned hinge 35 barrels 24 which receive a hinge rod 25 which extends substantially the full height of the door.

The outer ends of the leaves 22 are provided with hinge barrels 26 which align 45 with hinge barrels 27 carried by the side wall 15 of the garage and these barrels 26 and 27 receive a hinge pin or rod 28 which also extends substantially the full height of the door. It can be seen by this construction 50 that the door is hingedly connected to one side of the garage at one edge thereof.

A spring 29 is coiled about the hinge rod 25 and has its opposite ends anchored at 55 31 and 32 to the door sections 19 and 20 respectively and this spring normally tends to rotate the section 20 upon the hinge rod 25 toward and in abutment with the section 19.

In order to normally hold the door section 20 against swinging movement and the 60 door in its fully closed position a novel releasable trip mechanism 33 is provided for this purpose.

This means 65 33 comprises a rigid lock bar 34 riveted or otherwise secured to the door

section 20 and the outer end of this bar extends laterally beyond the free outer end of the door section.

A pivoted catch lever 35 is rockably secured to a face plate 36 which is bolted or otherwise secured to the side wall 16 of the garage B. This pivoted catch lever 35 extends forwardly from the side wall 16 of the garage and is disposed in the path of the rigid lock bar 34 and the lock bar is adapted 70 to engage in a notch 37 formed in the said pivoted catch lever 35 when the door is in its fully closed position. A guide plate 38 is carried by the face plate 36 and forms means for guiding the rigid lock bar 34 75 under the catch lever 35 during the closing movement of the door section 20. The pivoted catch lever 35 is normally urged downwardly into engagement with the rigid lock bar 34 by means of an expansion spring 39 80 which is coiled about a guide rod 40 mounted in suitable guides 41 secured to the said side wall 16.

In order to permit the raising of the catch lever 35 against the tension of the coil 90 spring 39, a rock shaft 42 extends through the side wall 16 and is provided with a lift lug 43 for engaging under the said pivoted catch.

An operating handle 44 is secured to the 95 outer end of the rock shaft 42 and it is obvious that by operating the handle 44 that the lift lug 43 formed on the shaft will be brought into engagement with the lower surface of the catch lever 35 for raising the 100 same.

It is to be understood at this point, that any desired mechanism can be connected to the handle 44 and arranged at a point distant from the garage door, so that the said catch lever can be operated by the occupant 105 of an automobile approaching the garage without necessitating the occupant from getting out of the automobile.

In order to permit the catch lever 35 to be operated from the interior of the garage the inner end of the rock shaft 42 has secured thereto, an operating handle 45.

Now when the catch lever 35 has been raised, it is obvious that the door section 20 110 will automatically swing open into engagement with the section 19 under the influence of the spring 29.

In order to permit the automatic opening of the door section 19, a spring 46 of the desired size and strength is coiled about the hinge rod 28 and the opposite terminals of this spring are secured as at 47 and 48 to the side wall 15 of the garage and the door section 19 respectively.

In order to normally hold the door section 19 against swinging movement under the tension of the spring 46 a pivoted catch lever 49 is carried by the upper edge of the door section 19 adjacent to the inner edge 125

thereof. By referring to Figure 10 of the drawing it can be seen that the pivoted catch lever 49 is rockably mounted at a point intermediate its ends upon a suitable bracket 50 which is bolted or otherwise secured to the said door section 19. The inner end of the lever 49 is provided with a tapered nose 51 and a notch 52 in its upper edge and a keeper plate 53 is bolted to the inner face of the front wall 17 of the garage B and disposed in the path of the lever. A contractile coil spring 54 is connected to the outer end of the lever 49 and to the garage door section 19 and this spring normally tends to hold the inner end of the latch lever 49 in a raised position.

When the section 19 of the door is swung to its closed position the inclined nose 51 of the lever 49 will engage the keeper plate 53 and the said lever will be swung downwardly until the notch 52 comes into alignment with the keeper plate 53 at which time the inner end of the lever will swing upwardly and the walls of the notch will engage the said keeper plate and thus hold the door section in its closed position. The outer end of the latch lever 49 is also provided with an inclined nose 55 for a purpose which will now be described.

The upper edge of the door section 20 has secured thereto a trip plate 56 which extends above the upper edge thereof. This trip plate is so arranged as to be in the path of the inclined nose 55 of the catch lever 49 when the door section 20 is being swung to an opened position.

Thus when the catch 35 has been released and the door section 20 swings open, the trip plate 56 will engage the nose 55 and swing the trip catch 49 moving the inner end thereof downward and out of engagement with the keeper plate 53. This will permit the inner door section 19 to swing open under the influence of the spring 46.

It is desirable to lock the sections 19 and 20 together during the opening movement of the door and a novel releasable lock is provided for this purpose, which will now be described.

The door section 19 is provided with a slot 57 adjacent to the pivot point thereof and suitable keeper plates are secured to the opposite faces of the door section and are provided with slots therein which are adapted to register with the slot 57 in the door section. The door section 20 adjacent to its outer end is provided with a slot 59 and slotted face plates 60 and 61 are secured to the outer and inner faces of the door on each side of the slot. The inner face plate 61 has formed thereon a suitable bracket 62 to which is pivoted a notched latch lever 63 which extends through the door. The portion of the latch lever 63 which projects beyond the inner face of the door section 20

is provided with a manipulating handle 64. Now when the door section 20 is swung upon the door section 19 the pivoted catch lever 63 will ride into the slot 57 and the notched end of the lever will engage the outer keeper plate 58. It is obvious that the catch will hold the two sections of the door releasably connected together.

In order to hold the door from swinging back too far and to hold the door in its opened position, a bracket 65 is secured to the side wall 15 of the garage and projects laterally therefrom adjacent to the front of the garage and this bracket 65 is braced by suitable straps 66 and 67. By referring to Figure 7 of the drawing it can be seen that the bracket 65 is disposed in the path of the door and thus the same will stop the door from swinging too far back and that the bracket also constitutes a keeper strap which is adapted to be engaged by the notched end of a pivoted latch lever 68 which is carried by the door section 20. This latch lever 68 extends through a slot 69 formed in the door section and is pivotally connected at its inner end as at 70 to a suitable face plate 71 connected to the door 20. The notched end of the latch lever 68 is provided with the usual inclined guide nose for engaging the keeper bracket 65 so as to cause the lifting of the lever when the door is swung to its opened position and the notched end of the lever is normally urged downward into the path of the keeper bracket by means of an expansion spring 72, the lower end of which engages a laterally extending lip 73 formed on the said lever. This spring 72 is coiled about a guide rod 74 carried by the lip and the upper end of this guide rod slidably extends through a guide bracket 75 formed on a face plate 76 secured to the inner face of the door section 20. The upper end of the expansion spring 72 engages the guide bracket 75 as clearly shown in Figure 4 of the drawing.

In order to permit the convenient operation of the latch lever 68 when it is desired to close the door after the same has been opened, a handle 77 is pivoted adjacent its upper end as at 78 to a suitable bracket 79 which is secured in any desired way to the door section 19. The extreme upper end of the handle 77 is provided with a right angularly disposed arm 80 which overlies the outer end of the latch lever 68. This handle 77 is of a sufficient size to permit the convenient gripping thereof by the hand of the operator of the door and it is obvious that when the handle 77 is pulled outwardly the same will be rocked and the arm 80 will engage the free end of the lever and lift the inner end thereof upwardly out of engagement with the guide and keeper bracket 65 and thus permit the swinging of the section 19 on its hinge to its closed position. It can

be seen that when the handle 77 is pulled for operating the catch 68, that this motion will also close the door thus facilitating the operation of the door.

5 In operation of the improved door, when it is desired to open the same it is merely necessary to actuate the handle 44 which will raise the latch lever 35, as heretobefore described, and the tension, of the spring 29 10 will swing the door section 20 on the hinge rod 25 into engagement with the door section 19. This will move the trip plate 56 into engagement with the outer end of the lever 49 causing the lowering of the inner 15 end thereof from out of engagement with the keeper plate 53. This will permit the opening of the door section 19 under the influence of the spring 46. Now as the door section 20 is swung into engagement with 20 the door section 19 the latch lever 60 will ride into engagement with the keeper plate 58 which will hold the two door sections locked together. As the door swings open under the influence of the spring 46 in engagement with the guide and keeper bracket 25 the latch lever 68 will ride into engagement with the said bracket and hold the door against accidental swinging movement.

Ready access can now be had to the interior of the garage or other body with which the door is associated.

When it is desired to close the door it is merely necessary to first grasp the handle 77 and actuate the latch lever 68 and the 35 door will be swung to its half closed position after which the handle 64 of the latch lever 63 is operated so as to move the latch lever from out of engagement with the keeper 63 and this movement swings the 40 door to its fully closed position. As the door section 20 is moved from out of engagement with the section 19 the trip plate 56 will ride out of engagement with the latch lever 49 permitting the latch lever to 45 again engage the keeper plate 53 carried by the upper portion of the front wall of the garage.

The arrangement of the door is such, that the same will open quickly without any likelihood of the same striking the operator of the door, in view of the small area of space the door occupies during the opening movement thereof. This is one of the most important features of the swinging folding 55 sections of the door.

From the foregoing description, it can be seen that a novel door has been provided of exceptionally simple and durable construction which will automatically fold and open 60 upon the releasing of a single catch.

Changes as to details may be made without departing from the spirit or the scope of this invention, but:—

What I claim as new is:—

65 1. The combination with a door frame

and a door including a pair of sections, means hingedly connecting one section to the door frame, means hingedly connecting the other section to the first mentioned section, of a door opening device including 70 resilient means normally tending to swing the second section on the first section, means normally tending to swing the second section to an opened position on the door frame, means normally holding the first section 75 against movement, means normally holding the second section against movement, and means operated by the first section for releasing the holding means of the second section upon opening movement thereof. 80

2. The combination with a door including sections hingedly connected together, and means normally holding the door in a closed position, of a door opening device including means for automatically swinging one door 85 section open at a time upon the manual release of said door holding means.

3. The combination with a door frame and a door hingedly connected thereto including hingedly connected sections, of a 90 door opening device including resilient means normally tending to swing the door on the door frame to an open position, a releasable catch normally holding the door closed, resilient means normally tending to swing one of the pivoted hinged sections in 95 abutting relation to the other section, a manually operable releasable catch for normally holding the mentioned hinge section against swinging movement, and means carried by said mentioned hinge section for engaging the first mentioned releasable latch. 100

4. The combination with a door frame and a door hingedly connected thereto including a pair of hingedly connected sections, of a door opening device including resilient means normally tending to swing the door on the door frame to an open position, a releasable latch normally holding the door closed, resilient means normally tending to swing one of the door sections in 105 abutting relation to the other section, a releasable catch for engaging the mentioned hinged section normally holding the same against swinging movement, a swinging lever arranged at one side of the door for operating said releasable catch, means carried by the mentioned door section for operating and releasing the first mentioned latch, and means for releasably locking the hinged 110 sections of the door together during the opening and closing movement of the door. 115

5. The combination with a sectional door, means hingedly connecting the meeting edges of the sections together, a door frame, 125 and means hingedly connecting the outer edge of one door section and the door frame, of a door opening device including resilient means for normally swinging the door section connected to the door frame to an open 130

- position, a releasable catch for normally holding the mentioned door section in a closed position, resilient means normally tending to swing one door section upon the other door section, a hand operated latch for normally holding the last mentioned door section against swinging movement, means carried by the last mentioned door section for operating the first mentioned catch when the last mentioned door section has swung to its opened position in abutting relation to the other door section, releasable means for connecting the door sections together, and releasable means for holding the door in its opened position against accidental movement.
6. The combination with a door frame, a door, a plurality of aligned strap hinges having the leaves thereof connected respectively with the door and door frame, a single hinge rod extending through the barrels of the hinges, of a door opening device including a spring coiled about said rod having its terminals connected respectively with the frame of the door normally tending to swing the door to an opened position, a bracket carried by the frame and projecting laterally therefrom for limiting the opening and swinging movement of the door, a releasable catch for normally holding the door in a closed position against said spring means, and a releasable catch carried by the door for engaging said bracket for holding the door against accidental swinging movement when the same is in its opened position.
7. The combination with a door frame, and a door including an inner and an outer section, means hingedly connecting the inner and outer sections together at their meeting edges, and means hingedly connecting the inner section at its outer edge to the door frame, of a door opening device including resilient means normally tending to swing the inner door section to an opened position on the door frame, a keeper plate carried by the door frame, a pivoted latch lever carried by the inner section of the door for engaging the keeper to normally hold the said door section against swinging movement, spring means normally tending to swing the outer section to an open position in abutting engagement to the inner section of the door, a releasable latch for normally holding the outer section of the door against swinging movement, and a trip plate carried by the outer section of the door arranged in the path of the latch lever carried by the inner section of the door and permitting the automatically releasing of the outer section of the door.
8. The combination with a door frame a door including inner and outer sections, means hingedly connecting the meeting edges of the inner and outer sections of the door together, and means hingedly connecting the inner section of the door to the door frame, of a door opening device including resilient means normally tending to swing the inner surface of the door open on the door frame, a releasable catch carried by the inner surface of the door for engagement with the door frame to hold the section against normal swinging movement, resilient means normally tending to swing the outer section of the door into abutting relation to the inner section of the door, a releasable latch for normally holding the outer section of the door against swinging movement, means carried by the outer section of the door for operating the catch carried by the inner section of the door permitting the swinging movement of the inner section of the door, a releasable catch carried by the outer section of the door for engaging the inner section of the door when the outer section is swung to an opened position in engagement with the inner section of the door, a laterally projecting bracket carried by the door frame for limiting the opening and swinging movement of the door, a latch carried by the outer section of the door arranged to engage the bracket when the door is swung to its fully opened position and an operating lever for the last mentioned latch carried by the inner section of the door.
9. The combination with a door frame and a door including an inner and an outer section, means hingedly connecting the meeting edges of the sections together and means hingedly connecting the inner section to the door frame, of an automatic door opening device including spring means normally tending to swing the inner section open on the door frame, releasable means normally holding the inner section against swinging movement, resilient means normally tending to swing the outer door section on the inner door section into abutting engagement therewith, means carried by the outer door section for actuating said releasable means, a latch bar carried by the outer door section and projecting laterally therefrom, a pivoted latch lever carried by the door frame arranged to engage the latch bar, a rock shaft for operating said latch lever, and handles secured to the inner and outer ends of the rock shaft for permitting the operation thereof.
10. The combination with a door frame and a door including inner and outer sections, means hingedly connecting the meeting edges of the sections together, means hingedly connecting the inner section to the door frame, spring means normally tending to swing the inner section to an opened position on the door frame, a laterally extending bracket carried by the door frame, arranged in the path of the inner section to limit the swinging movement thereof, a releasable

catch arranged to normally hold the inner section of the door against swinging movement, resilient means normally tending to swing the outer section of the door on the 5 inner section of the door into abutting engagement therewith, means carried by the outer section of the door for engaging the catch, a releasable catch carried by the outer section of the door for holding the same 10 against swinging movement, a pivoted catch carried by the outer section of the door arranged to engage the laterally extending bracket when the door is opened to its full extent to prevent accidental closing movement of the door, said latch lever extending 15

through the outer section of the door, a rock lever extending through the inner section of the door and pivotally secured thereto arranged to engage the inner end of the pivoted latch carried by the outer section of the 20 door when the outer section of the door is in its opened position, and a hand grip formed on said lever arranged to overlie the inner face of the inner section of the door.

In testimony whereof I affix my signature 25
in the presence of two witnesses.

WILLIAM M. KARR.
